BRASSIÈRE

Irving Schenkman, Brooklyn, N. Y.

Application June 23, 1947, Serial No. 756,351

2 Claims. (Cl. 2—42)

1

This invention relates to brassières, and, more particularly, aims to provide new and useful improvements in a brassière (whether of the bandeau type or of the full-waist type or otherwise) of the kind comprising a garment to be worn about the body below the arms and including pouches for receiving and lifting the breasts or members of the bust, such garment also having a pair of adjustable shoulder straps each connected at its opposite ends to front and back points on the garment.

In connection with a brassière, and one made, as is necessary and as heretofore has been the practice, of soft pliable material particularly at and adjacent the bust pouches, and so made of a material with inadequate form holding stiffness, an object is to provide a means for overcoming the defect just mentioned and at the same time for supporting the bust in a more comfortable and satisfactory way than was possible in previous garments intended for the purpose.

In attaining this object, a feature of the invention is the provision, in combination with the usual or any outer section of soft pliable material, of an inner one-piece auxiliary fabric wall or section for each breast or bust member. Each of these auxiliary sections, which are preferably stitched together or otherwise made unitary with each other, are so constituted that it performs a novel and valuable plurality of functions.

The lower part of each of said inner auxiliary sections, by virtue of the fact that such section is attached at its lower part to the remainder of the garment in a particular way and by special combinations of particularly located and related lines of stitching, acts as a form shaping means for the entire garment, because the latter is thereby stiffened where it has always needed stiffening.

At the same time, the upper part of each of said auxiliary sections, above its said stitchings, has therein an opening of a size and shape to encircle loosely the basal or root end of a bust member, thereby to provide a floating or largely free collaring or sling means for the bust member received and lifted in the forwardly adjacent pouch.

The upper end of each auxiliary section, which section is wholly of inelastic material, is connected above the top of its said collaring or sling means for the bust member, by a relatively short non-elastic tape or the like with an upper point on the main or outer section or portion of the

garment above the pouch of the latter which receives and lifts said bust member.

Thereby, the upper portion of each inner auxiliary section is so connected to the main garment that, although said collaring or sling means lies against the body close under a pouch surrounding portion of the outer section of the garment, there may be when needed some relative movement between the collaring or sling means and the associated pouch, thus increasing to a marked degree freedom from occasional physical discomfort and strain.

Moreover, the combination of new parts so far described acts as an anti-bust-sagging means strikingly superior to any prior proposal of which applicant is aware, including even special wiring.

Another object of the invention, and one particularly making for prevention of bust discomfort, has to do with an improved method of darning the piece of material from which each pouch is cut.

In order to obtain the required shape for the pouch, it has heretofore been the custom, as is well known, to cut out a portion of said piece of material; such cut-out being a V-shaped one with the apex of the V directed toward but located some distance from what is to be the center of rotundity of the pouch. Said cut-out has not only had the apex of the V thus spaced away from said pouch center, but, also, the cut-out has been so placed that when the garment is completed and worn the seam resulting from stitching together the edges of the cut-out is obliquely inclined to the vertical. These precautions have previously been thought necessary to avoid irritating the sensitive parts of the bust; but at the cost of not obtaining an ideally shaped pouch.

According to the present invention, the dart used at the pouch is extended vertically upward to above what will be the true center of rotundity of the pouch, giving the ideal pouch shape, yet a seamed dart which, it has been found, is less irritating than the previous seamed dart, because, in stitching together the edges of the new cut-out, a part of the concept of the invention in this regard is to use a particular, and an especially soft, seam. This special seam may be described as a darted seam stitched as a French seam.

Still another feature of the invention has to do with the shoulder straps, which, as previously made, have had a frequent tendency to chafe the tops of the shoulders; the present invention providing cushion-soft additions to the under sur-

faces of those parts of the shoulder straps which lie on the shoulder tops.

For further comprehension of the invention, and of the objects and advantages thereof, reference will be had to the following description and accompanying drawing and to the appended claims in which the various novel features of the invention are more particularly set forth.

In the accompanying drawing forming a material part of this disclosure:

Fig. 1 shows a brassière pursuant to the invention, spread out, looking toward the inner side of the garment.

Fig. 2 is a similar view, but looking toward the outer side of the garment.

Fig. 3 is a fragmentary perspective view, looking toward the inner side of the garment in the region of the bust member serving structure seen at the right in Fig. 1, with the inner auxiliary bust member collaring and sling section shown pulled inwardly away from the main outer section of the garment, and with the associated shoulder strap omitted, to make clear features of construction not so clearly shown in the other views.

Fig. 4 is a detail view, being a section taken on the line 4—4 of Fig. 3.

Fig. 5 is a similar view, being a section taken on the line 5—5 of Fig. 3.

Referring to the drawing in detail, the brassière comprises an outer section 10 of relatively soft fabric or other equally pliable material provided with two bust member receiving pouches 11, 11 of a similarly soft and pliable fabric.

As here shown, said outer section is formed of two intermediate-like soft and pliable fabric pieces 12, 12, each providing one of the two pouches 11, and two like soft and pliable end fabric pieces 14, 14. At their meeting edges the intermediate fabric pieces 12 are suitably stitched together to join them as indicated at 15 in Fig. 2, and the meeting edges of each piece 12 and the adjoining end piece 14 are stitched together to join them as indicated at 16, 16 in Fig. 2.

Extended over the inwardly bent edges of the adjacent pieces 12 and 14 along the vertical seams 16, there are substantially vertically extended tapes 17. The vertically extending side edges of the tapes are secured to the adjacent pieces 12 and 14 by lines of stitches 18. Similarly, a tape 19 is placed as shown in Fig. 1, and this tape is also secured to the two pieces 14 by two lines of stitching 20, 20.

The tape 19, while shorter than the tapes 17, is, it will be noted, wider than the latter.

These tapes 17 and 19 not only finish three seams at the inner side of the outer section 10, but, in combination with the inner auxiliary sections 21, 21, and with the tape stitchings 18 and 20 and others of the special stitchings aforesaid, and with the downwardly converging inclinations of the tapes 17, provide the garment stiffening means of the invention.

In this connection it is pointed out that the major lower lengths of the stitchings 18 seen in Fig. 1 go not only through the tapes 17 and the adjacent pieces 12 and 14 of the outer section 10 but also through the adjacent inner sections 21, along lower straight sides of the latter where extended under the tapes 17. Similarly, the stitchings 20 in their entirety go also through the two inner sections 21 along the lower straight sides of the latter where extended under the tape 19.

Referring now to said special stitchings, these are the stitchings 22, arranged as shown, the

upper several of which are extended along lines of substantially W-extension. The stitchings 22 go through the inner sections 21, the pieces 12 of the outer section, and the tapes 17 and 19; and some of the lower stitchings 22 go also through an edging tape 23 extending all along the bottom of the garment between the outer ends of the pieces 14.

Below the uppermost stitching 22, therefore, the bottom parts of the inner sections 21 are in effect quilted to the outer section 10; such quilting and consequent stiffening, relative to the garment at each piece 12 of the outer section, being at its top middle, this the lowermost portion across its top, is so placed that it establishes the bottom rotundity of the adjacent pouch 11, and at the same time follows the bottom rotundity of the bust member collaring and sling opening 24 in the adjacent inner section 21.

Each section 21, further, is locked to the outer section 10, up to the top of the tape 19, and up to a corresponding height on each tape 17, as already explained, by the lower major lengths of the stitchings 18 and by the stitchings 20.

Thus the upper part of each inner section 21 is entirely free from the outer section 10, as shown best in Fig. 3, and is partially free from the outer section between the uppermost stitching 22 and a higher point marked at one side by the top of tape 19 and at the opposite side of said inner section 21 by the upper limit of the portions of the stitchings 18 which go through said inner section.

At its top each opening 24 is completed by overlapping and stitching together the free ends of two horn-like extensions 25 from and integral with the lower main portion of the inner section 21; thereby to make it possible to arrange the material of said section 21 marginal to the opening so that this marginal material may set itself when the garment is worn to present a rearwardly facing shallow cup throughout of non-stretchable material.

Joining the top of each inner section 21 and the high point of each opposite piece 12 of the outer section 10, and stitched at its opposite ends to these points, is a relatively short length of non-elastic tape 26.

Connecting each tape 26, by means of a suitable buckle 27 through which said tape slidably extends, is a shoulder strap 28 passing at one end through said buckle for length adjustment of the strap, and stitched at its other end to a point near the outer end of that one of the pieces 14 of the outer section 10 which is directly alongside the piece 12 with which said strap is associated.

The seamed dart for each pouch 11 is indicated at 29, made in a particular way pursuant to the invention, as will later be explained.

The strap 28 is a narrow tape formed by longitudinally plurally folding a strip of light material to give it finished edges and longitudinally stitching the strip at 30, in accordance with practice familiar in the art. To avoid chafing by the narrow shoulder straps at the top of the shoulders, there is stitched to each strap a member 31 of soft-cushiony material, as plush; this member being slightly wider than the strap and extended over a suitable length of the strap at the surface thereof which will be its bottom surface when the strap is arranged over a shoulder of the wearer of the brassière.

The left hand end of the left hand piece 14 in Fig. 1 is edge finished by the tape 32, held in place all along its length by suitably stitching as indi-

cated. This tape continues along the top of said piece 14, then along the tops of both pieces 12 of the outer section 10, and then along the top of the other piece 14. The third edge finishing tape for the outer section 10 is the tape 33.

Suitably anchored in place at the end of the garment to which the tape 33 is applied are a pair of hooks 34, for selective engagement with either the pair of eyes 35 or the pair of eyes 36, these eyes carried at the opposite end of the garment; one pair of eyes at the joinder line of a terminal piece 37 and an elastic insert 38^a between said piece 37 and the adjacent piece 14 of the outer section 10, and the other pair on the piece 37, which latter has stitched thereto an edge finishing tape 38.

An edge decorative ruching 39, of net, is shown as extended all along the top of the outer section 10; in which connection Fig. 5 should be noted. The front of the outer section 10 may be variously decorated; for instance, lengths of fairly wide lace 40 may be added by stitchings 41 as indicated in Figs. 1 and 3.

Referring to the darted seam 29 for a pouch 11, Fig. 4 should now be examined in connection with Figs. 1 and 3. As already stated, the V-shaped cut-out in each piece 12 is extended vertically upward to above what will be the true center of rotundity of the pouch; but at the same time stitchings are applied to marginal portions of the dart cut-out to provide a special seam stitched as a French seam. First said marginal portions are stitched together as shown at 42 in Fig. 4, and next the stitching 43 is applied as shown in said view; this last being the only exposed stitching. Note the stitching 43 in Figs. 1 and 3, on the inner face outer section 10 of the garment. Neither of the stitchings 42 and 43 is seen in Fig. 2, but this view indicates at 44 that the finally provided darted seam 29 extends upward from the bottom of a piece 12 to a rather high point along the height of its pouch 11.

While I have illustrated and described the preferred embodiment of my invention, it is to be understood that I do not limit myself to the

precise construction herein disclosed and the right is reserved to all changes and modifications coming within the scope of the invention as defined in the appended claims.

Having thus described my invention, what I claim as new, and desire to secure by United States Letters Patent is:

- 5 1. In a brassière having a bust receiving pouch enclosing an inner auxiliary sling section with a shoulder strap having its front end terminating at a point above the pouch, parallel lines of downwardly arched stitches securing the bottom edge portion of the sling section to the bottom edge portion of the pouch, a buckle mounted on the free front end of the shoulder strap, and a tape having its ends secured to the adjacent top edge portions of the pouch and sling section, said tape having its intermediate portion slidably extended through said buckle.
- 10 2. In a brassière having a bust receiving pouch enclosing an inner auxiliary sling section with a shoulder strap having its front end terminating at a point above the pouch, parallel lines of downwardly arched stitches securing the bottom edge portion of the sling section to the bottom edge portion of the pouch, a buckle mounted on the free front end of the shoulder strap, and a tape having its ends secured to the adjacent top edge portions of the pouch and sling section, said tape having its intermediate portion slidably extended through said buckle, said tape being formed of non-elastic material.

IRVING SCHENKMAN.
